UNITED STATES PATENT OFFICE.

GEORGE H. WILSON, OF LOUISVILLE, KENTUCKY.

VACUUM CAP FOR SMOKERS' PIPES.

Application filed June 29, 1925, Serial No. 40,307.

This invention relates to smokers' appliances and has particular reference to an attachment for smoking pipes.

The object of the invention is to provide a cap for sealing in fire-proof manner the top of the bowl of the pipe, thereby rendering the use of the pipe safe about barns and garages, said cap being provided with a chamber above the bowl, the joint between the cap and the pipe being close enough to cause the creation of a partial vacuum within the cap by draft upon the pipe, resulting in a number of advantageous features from the smoker's point of view, among which are improvement in the combustion of the tobacco, coolness of the smoke, reduction in the amount of "cake" collecting upon the sides of the bowl, and regulation of the rapidity of the combustion according to the grade of the tobacco.

In the drawings:—

Figure 1 is a sectional elevation of one form of the vacuum cap, the pipe to which it is applied being shown in broken lines.

Figure 2 is a side elevation of the same.

Figure 3 is a perspective view showing the underneath side.

Figure 4 is a side elevation of a slightly modified form of the invention.

Figure 5 is a perspective view of the latter form showing the under side thereof.

Referring now in detail to the several figures, the numeral 1 represents a cap having imperforate top and side walls arranged to

fit tightly upon the upper end of the bowl of a pipe, as shown. In Figure 1 the cap is shown as internally threaded at 2 and as

screwing upon corresponding threads formed externally of the pipe bowl. In

Figure 4 the skirt 3 of the cap is shown as not threaded, being designed to fit upon the bowl of the pipe with frictional engagement.

In either case the fit is presumed to be so tight that while the entrance of a little air

is permitted, the amount admitted is insufficient to prevent the formation of a partial vacuum in the cap when suction is applied to the pipe stem.

A partition 4 extends across the interior of the cap forming between said partition and the top wall of the cap a vacuum chamber 5. The partition 4

preferably, but not necessarily, rests upon the upper end of the pipe bowl. Said partition is formed with an aperture 6 and the

invention contemplates the provision of a plurality of caps having partitions with

apertures of different areas, the object of which will shortly appear.

When the smoker draws upon the stem 7 of the pipe the air in the vacuum chamber 5 is attenuated, causing a partial vacuum. In its downward passage through the tobacco the air exhausted from the chamber 5 promotes and supports combustion. When the smoker opens his mouth to release the smoke 65 there is an in-rush of cool air through the stem of the pipe and through the body of tobacco in the bowl into the vacuum chamber. Not only is combustion of the tobacco thereby assisted and sustained, but between 70 each draft of smoke through the stem, there is an alternate back draft of cool air, cooling the stem and adjacent parts of the pipe thereby adding to the comfort of the smoke. A cooling of the air is also promoted to some extent by the adiabatic expansion of the air into the vacuum chamber.

The rate of flow of the tidal surge of air into and out of the vacuum chamber depends upon the size of the aperture 6. When there is very 80

little licorice in the tobacco or where it is more or less dry, a cap having a small aperture 6 is selected since this size is adapted

for slow combustion. Where the tobacco is moist, a cap with a larger aperture may be 85

used, the velocity of flow of air through the combustion chamber in both directions being thereby increased with a corresponding acceleration of combustion.

For convenience in removing the cap to 90 fill the pipe I have shown it provided with a knurled grip 8.

It is obvious that while my invention is simple in construction, yet there are numerous ways in which the inventive principle 95 may be physically embodied without departing from the scope of the appended claims.

Having described my invention what I claim as new and desire to secure by Letters Patent, is:—

1. An attachment for smoking pipes, comprising a cap constructed to enclose a vacuum chamber within said cap above the level of the upper edge of the bowl of said pipe, the cap fitting the bowl with sufficient tightness to prevent the entrance of air to the pipe bowl in sufficient quantity to prevent the formation of a partial vacuum within said cap when suction is applied to the pipe stem.

2. An attachment for smoking pipes, comprising a cap fitting the bowl of the pipe with sufficient tightness to prevent the en-

france of air to the pipe bowl in sufficient quantity to prevent the formation of a partial vacuum within said cap when suction is applied to the pipe stem, and provided with a partition extending thereacross defining a chamber between said partition and the wall of said cap, said partition being formed with a restricted aperture establishing communication between said chamber and the bowl of said pipe.

3. An attachment for smoking pipes, comprising a cap adapted to form a closure for the bowl of a pipe, said cap fitting the bowl with sufficient tightness to prevent the entrance

of air to the pipe bowl in sufficient quantity ¹⁵ to prevent the formation of a partial vacuum within said cap when suction is applied to the pipe stem, said cap being provided with a partition extending thereacross ²⁰ defining a chamber between said partition and the top wall of said cap, said partition being adapted to seat upon the top of said bowl and having a restricted aperture establishing communication between said chamber and bowl.

In testimony whereof I have hereunto set my hand.

GEORGE H. WILSON.
